The ornamental design of a land clearing tool interface, as shown and described.

DESCRIPTION

FIG. 1 is a front, right, perspective view of a land clearing tool interface showing our new design;

FIG. 2 is a rear, left, perspective view thereof;

FIG. 3 is a top view thereof;

FIG. 4 is a right side view thereof;

FIG. 5 is a front view thereof;

FIG. 6 is a left side view thereof;

FIG. 7 is a back view thereof; and,

FIG. 8 is a bottom view thereof.

The broken line showing of portions of the tool interface is included for the purpose of illustrating portions of a land clearing tool interface and forms no part of the claimed design.
